[57] CLAIM

The ornamental design for a switch case bezel, as shown and described.

DESCRIPTION

FIG. 1 is a perspective view of a switch case bezel showing my new design;

FIG. 2 is a top plan view thereof;

FIG. 3 is a side elevational view thereof, the opposite side being a mirror image;

FIG. 4 is an end elevational view thereof, the opposite end being a mirror image;

FIG. 5 is a bottom plan view thereof;

FIG. 6 is a sectional view thereof taken along line 6—6 of FIG. 4; and

FIG. 7 is a sectional view thereof taken along line 7—7 of FIG. 2.

The broken line disclosure of the switch case shown in FIGS. 1-5 is for illustrative purposes only and forms no part of the claimed design.
